POST DRIVER

Ole A. Dirksen and Harold G. Beesley,
Spencer, Iowa

Application July 8, 1944, Serial No. 544,108

6 Claims. (Cl. 61—74)

This invention relates to a post driver and it is primarily an object of the invention to provide an apparatus of this kind which can be readily and conveniently mounted upon a portable body, such as a truck or tractor, and wherein the apparatus is particularly adapted and designed for use in the driving of fence posts and more especially in the erecting of snow fences along highways.

The invention also has for an object to provide a member mounted for reciprocating movement and which is provided at its outer or upper end portion with a driving hammer, together with driven means for intermittently engaging the moving member to raise the same, said member dropping by gravity in the periods intermediate the raising operations.

Another object of the invention is to provide an apparatus of this kind comprising a fixed member and a reciprocating hammer-carrying member operatively engaged therewith, together with friction means carried by the fixed member for intermittent engagement with the moving member to raise the same.

A still further object of the invention is to provide an apparatus of this kind including a fixed member and a hammer-carrying member engaged therewith for reciprocating movement and wherein a rotating element for frictional engagement with the movable member is constantly urged into such engagement to impart raising or lifting movement to the movable member, together with means for intermittently releasing the friction member from the movable member to allow the movable member to drop.

The invention consists in the details of construction and in the combination and arrangement of the several parts of our improved post driver whereby certain important advantages are attained, as will be hereinafter more fully set forth.

In order that our invention may be better understood, we will now proceed to describe the same with reference to the accompanying drawings, wherein:

Figure 1 is a view in side elevation of a post driver constructed in accordance with an embodiment of our invention;

Figure 2 is a view in rear elevation of the device as illustrated in Figure 1;

Figure 3 is a vertical sectional view taken substantially on the line 3—3 of Figure 2;

Figure 4 is an enlarged detailed sectional view taken substantially on the line 4—4 of Figure 1;

Figure 5 is an enlarged detailed sectional view taken substantially on the line 5—5 of Figure 1;

Figure 6 is a fragmentary view, partly in elevation and partly in section, showing the power unit in released position;

Figure 7 is an enlarged detailed fragmentary view, partly in section and partly in elevation, showing the power unit in effective position; and

Figure 8 is a sectional view taken transversely 10 through the central portion of Figure 7, with parts in plan.

In the embodiment of the invention as disclosed in the accompanying drawings, the apparatus comprises a base member or plate 1 adapted to be suitably anchored to a portable unit U, which may represent a truck or tractor, and extending upwardly from this base member or plate 1 and rigid therewith is a relatively long channel member 2 of desired dimensions and 20 which has its side flanges a outwardly disposed with respect to the unit U.

Snugly and slidably engaged with the member 2 between the side flanges a thereof is an elongated movable member 3, also shown as of channel type, and which is provided at its outer or top portion with a driving hammer 4 of required dimensions which, in the movements of the member 3, will readily pass between the flanges a of the fixed or main member 2.

30 The side flanges a of the member 2 at the upper and lower portions thereof are provided with the arms 5 extending outwardly beyond the open face of the member 2 and each of said extended portions is provided with an inwardly directed 35 trunnion or stub shaft 6 on which is mounted a roller 7 having contact with the outer or free longitudinal edge of a side flange b of the member 3, whereby the member 3 is effectively held within the member 2 yet free for endwise movement in either direction. Each of these rollers 7 is preferably of a ball bearing type.

Pivotedly connected with the lower portions 45 of the flanges a of the member 2, as at 8, are the links 9 which extend rearwardly of the member 2 and are pivotally connected, as at 10, to the side plates 11 of the power unit P. These plates 11 are of desired length and extend upwardly upon the rear side of the member 2 and closely adjacent thereto and said plates 11 are maintained 50 in desired spaced relation by the interposed top block 12 and bottom plate 14.

The top block 12 has freely disposed there-through a bar or rigid member 15 extending outwardly from the intermediate or web portion c 55 of the channel member 2 and which is of a

length to extend a material distance outwardly beyond the block 12. This rod is provided at its outer end with the head 16. Interposed between this head 16 and the top block 12 is an expandable member 17, herein disclosed as a coiled spring, encircling the portion of the bar or member 15 which extends beyond the block.

This spring 17 is of considerable strength and serves to constantly urge or swing the unit P toward the member 2 to bring the friction roller 18 of the unit P into requisite contact with the intermediate or web portion *d* of the channel member 3 to effect the desired or lifting movement of the member 3. The intermediate or web portion *c* of the member 2 is provided with a suitably positioned opening 19 to allow for such contact.

The roller 18 is positioned between the plates 11 and is fixed to rotate with the shaft 20 which is disposed through the bearings 21 of the plates 11. The shaft 20 outwardly of one of the bearings 21 has fixed thereto a gear 22 which is constantly in mesh with a gear 23 carried by a driven shaft 24. The ratio of the gears 22 and 23 is such as to assure the desired peripheral speed of the roller 18.

The shaft 24 is disposed through and rotatably supported by the outstanding bearings 25 carried by the extended portions of the rearwardly disposed bracket arms 26. The shaft 24 is adapted to be driven from a suitable source of power, as from the power take-off shaft of a tractor or from the suitably operated drive shaft on a truck as by a belt operatively engaging a pulley 27 fixed to an extended portion of the shaft 24.

The shaft 24, in the present embodiment of the invention, carries for rotation therewith an elongated cam member 28 which has its ends disposed in the transversely disposed slots 29 provided in the plates 11. This cam member 28 has an extended eccentric portion 30 which has its high point disposed centrally of a particular heel 31 disposed on substantially the same radius as the outer flat end portion 32 of a slot 29.

When the high point of the extended or eccentric portion 30 of the cam member is disposed beyond the flat portions 32 of the slots 29, the expandable member or spring 17 will maintain the roller 18 in such contact with the intermediate or web portion *d* of the member 3 as to raise or lift the member 3 until the extended or eccentric portion 30 of the cam member 28 contacts the outer flat portions 32 of the slots 29, whereupon the unit P will be swung away from the member 3 a distance sufficient to free the roller 18 from contact with the member 3 and for a period of time to allow the member 3 to drop by gravity to bring the driving hammer 4 into desired impact with a fence post or the like to be driven. It is to be pointed out that the slots 29 are of a width in excess of the distance between the axial center of the shaft 24 and the high point of the cam member 28.

The member 2 at a desired point above the unit P has extending outwardly from its intermediate or web portion *c* a tubular sleeve 33 in which is slidably mounted a spring-pressed latch bolt 34 which is adapted to pass through the properly positioned opening 35 in the intermediate or web portion *c* of the member 2 to operatively engage within an opening 36 or the like in the intermediate or web portion *d* of the member 3 when the member 3 has been raised or

lifted to a desired point to hold said member 3 against dropping. This is of advantage when the apparatus is being transported from one place of operation to another. The latch member 34 will be operated in any manner preferred but in the present embodiment of the invention, the retraction of the latch member 34 is effected through the medium of a cam lever 37.

From the foregoing description it is thought to be obvious that a post driver constructed in accordance with our invention is particularly well adapted for use by reason of the convenience and facility with which it may be assembled and operated.

15 We claim:

1. An apparatus of the class described comprising a suitably supported guide member, a sliding member operatively engaged therewith for vertical movement, a hammer head carried by the sliding member, said sliding member and head dropping by gravity, a rotatable means movable relative to the second member and head for engaging the same and applying upward thrust thereto to raise the latter, and a second rotatable thrust means operating synchronously with the first thrust means to intermittently move and disconnect said first thrust means from the sliding member.

2. An apparatus of the class described comprising a guide, a member carried thereby for vertical sliding movement, a driving head carried by the member, said member and driving head dropping by gravity, a friction roller, means supporting said friction roller on the guide for movement into and out of contact with the sliding member, means constantly urging the supporting means toward the sliding member to bring the roller into frictional contact therewith, means for rotating the friction roller in a direction to raise the sliding member and the driving head when the friction roller is in contact with the member, and means having driving connection with the friction roller for intermittently freeing the friction roller from the sliding member to allow the latter and head to drop.

3. An apparatus of the class described comprising a guide member, a second member slidably carried thereby, a driving head carried by the second member, a rotating member carried by the guide member, means supporting said rotating member for movement into and out of driving connection with the second member, means constantly urging the supporting means toward the second member to effect connection of the rotating member with the second member, and a rotary thrust means turning synchronously with the rotating member for intermittently moving the supporting means and rotating member away from the second member after the latter has been raised, to permit said second member and driving head to drop.

4. An apparatus of the class described comprising an upstanding member, a second member slidably engaged therewith, a driving head carried by the second member, a power unit including a roller, means for mounting the power unit upon the first member for movement toward or from the second member, means for constantly urging the power unit toward the second member to bring the roller in operative engagement with the second member, a driven shaft carried by the first member for rotating the roller in a direction to move the second member upwardly when the roller is in contact with said second member, means carried by the shaft co-acting with the

power unit for intermittently moving the power unit to free the roller from the second member to allow said second member to drop, and the said means for outwardly moving the power unit comprising a cam carried by the shaft, the power unit having a member having an opening in which the cam extends, said cam intermittently contacting a part of the wall of the opening as the shaft rotates for moving the unit outwardly.

5. Apparatus of the character stated comprising a guide structure, a relatively long element supported by the guide for vertical movement, a driving head carried by said element, a frame supported on the guide for oscillatory movement toward and away from the element, resilient means normally urging the frame toward the element, a rotatable thrust member supported upon the frame and adapted to have driving connection with said element upon predetermined

movement of the frame toward the element, a rotatable cam supported by the guide adjacent to the frame, means forming a part of the frame providing a contact surface for the cam, the cam and rotary member being connected for simultaneous rotation, and means for imparting rotary movement to the cam and rotary member, the cam being arranged to have intermittent contact with said contact surface to effect the oscillation of the frame and intermittent connection of the rotary member with said element.

10 5. Apparatus of the character stated in claim 5, with latching means carried by the guide and adapted for connection with said element to 15 maintain the latter in a prescribed position against movement by gravity.

OLE A. DIRKSEN.
HAROLD G. BEESLEY.
